GARMENT CLASP

Ludwig Stark, West New York, N. J.

Application September 23, 1939, Serial No. 296,215

6 Claims. (Cl. 24—250)

This invention relates to garment clasps adapted for use with garters, suspenders and the like. The object of the invention is to provide a construction which shall be neat and compact having few parts, and easily assembled.

Another object is to provide a clasp in which the jaw elements are held in operative relationship without the use of pivot pins or the like.

Another object is to provide a garment clasp in which wire springs and the like are eliminated and an easily constructed flat spring of great durability is employed.

Other objects and advantages will be apparent by reference to the following specification and drawing showing a preferred embodiment of the invention it being understood however, that changes in details of construction can be made without departing from the appending claims.

In the drawing:

Figure 1 is a rear elevational view of the improved clasp;

Figure 2 is a side view of the clasp, Fig. 1;

Figure 3 is a front view of the clasp;

Figure 4 is a side view of the clasp as shown on the preceding figures with the movable jaw member open;

Figure 5 is a sectional view on the line 5—5, Fig. 1;

Figure 6 is a view of the blank from which the rear stationary jaw member is formed;

Figure 7 is a view of the stationary jaw showing the spring member in place therein;

Figure 8 is a sectional view on the line 8—8, Fig. 7;

Figure 9 is a view of the spring member;

Figure 10 is a perspective view of the movable jaw member; and

Figure 11 is a perspective view of the locking member.

It will be understood that the drawing is on a slightly enlarged scale and that the clasp can be made of any suitable dimensions.

The stationary jaw member 10 is made from a flat blank as shown in Fig. 6 of brass or other suitable metal and this is bent upwardly along its side edges to form flanges 11, 11a which have extensions forming outwardly projecting ears 12, 12a which are provided with the cam slots 13, 13a.

The upper end of the blank 10 is formed as shown in Fig. 6 with an additional pair of laterally projecting ears 14, 14a and an upper end extension 15 and these ears and the extension are folded forwardly and then downwardly as shown in Figs. 7 and 8, and the extreme end of the extension 15 is turned inwardly to form the downwardly projecting tongue 15a adapted to hold the spring member 16 and the movable jaw member 17 to be presently described.

The lower end 10a of the blank is bent forwardly and is shaped to form a gripping member

and if desired, the edges of same may be serrated or provided with teeth.

It will be seen that the flanges 11, 11a and the forwardly bent portions 15 and 10a form a housing for the spring 16 and that this spring projects upwardly below the pocket 15b formed by the inner walls 15, 15a of the blank. This pocket 15b receives the tongue 17a of the movable jaw member 17.

10 The spring member 16 is preferably made to overlie the inner surface of the housing previously described, but of course may be made narrower than the housing and if so, it will be held in place by its ends coming in contact with the flanged ends 15 and 10a of the blank 10. In any event, the spring member is suitably formed to exert tension on the movable jaw 17. A preferred form of spring is shown in Fig. 9 which comprises a rectangular piece of sheet steel which is laterally bowed giving it an arcuate form so that the center 16a thereof projects upwardly to engage the outer surface of the bend 17a of the movable jaw member.

20 The movable jaw member 17 is formed with an upwardly extending upper end forming the bent tongue 17a and has a downwardly extending gripping portion 17b which may be serrated or provided with teeth. The spring 16 having been assembled to the stationary jaw member, the assembly being shown in Fig. 7, the movable jaw member is added by merely pushing the tongue 17a thereof underneath the inwardly projecting tongue 15a of the stationary jaw 10 as shown in Fig. 5. The spring 16 pressing outwardly on the outer surface or heel of the bend of the tongue 17a tends to force the jaws 10 and 17 apart.

25 The jaws 10 and 17 having been thus assembled as just described, the locking member 18 is attached thereto by springing the cam ears 18a, 18b of said member inwardly, and then bending them outwardly until they freely fit in the slots 13, 13a of the stationary jaw. The ears 18a, 18b will now overlie the movable jaw 17 as shown in Fig. 3 and hold said movable jaw in place regardless of whether the clasp is in open or closed position.

30 By reference to Fig. 2 it will be seen that the ears 18a, 18b ride over and are held in locked position by the flat portion 13b of the slots and when in the position shown in the figure, the movable jaw is forced down against the stationary jaw 10 and the jaws are adapted to grip anything placed between them.

35 By reference to Fig. 4, it will be seen that when the locking member 18 is moved downwards as indicated by arrow 19, that the ears 18b ride upwardly along the flat portion 13b of the slots 13, 13a. This permits the movable jaw 17 to open as shown in the figure.

40 The rear ends of the slots 13, 13a cooperate with the rear edges of the cam ears 18, 18a to give a camming action between the locking member

18 and the stationary jaw 10 in order to securely hold the movable jaw 17 in place as shown in Fig. 2, and the shape of these slots 13, 13a is such as to permit an easy and free movement of the locking member from open to closed position. When in a closed position, the locking member 18 is prevented from extreme forward movement by the ears 14, 14a.

It will be observed that the spring 16 tends to open the clip when the locking member is in the position shown in Fig. 4 by reason of the fact that the bowed portion 16a of the spring projects upwardly and tends to press the movable jaw 17 outwardly, the motion of the jaw being limited by the end 17a thereof which is confined within the pocket 15b at the upper end of the stationary jaw 10 and that when the clip is in locked position shown in Fig. 2, the pressure of the movable jaw 17 on the spring 16 tends to flatten out the bowed portion 16a thereof so that the full tension obtainable from the inherent tension of the whole width as well as the length of the spring member is utilized thereby obtaining a long-lived spring positive in action and which can be made from a single piece of flat metal rolled with the bowed portion 16a therein as shown, and then cut to proper length, thus enabling this part to be simply and easily constructed. This eliminates the difficulties inherent when wire springs are used, which wire springs must be plated or otherwise treated to prevent rust which treatment is more difficult than in the case of flat springs of the type herein described.

It will also be observed that as there are no pivot pins used to secure the jaws together, the work incident to the insertion and securing of said pivotal pins in place is eliminated, and that the complete clasp consists of only four pieces, to wit: two jaws, the spring and the locking member, all of which are readily punched, formed and assembled with a minimum of labor and material.

As the edge of the tongue 15a engages the sharp bend in the tongue 17a, the movable jaw member 17 rides on what may be termed a knife edge and this knife edge support extends the full width of both jaw members which, by this construction are interlocked at this point and held in position by means of the spring 16. This provides a large wearing surface and eliminates any lateral twist or play in the movable jaw member 17 which is at all times yieldingly but properly supported by the spring 16, this motion being limited to that incident to approaching and receding from its associated member 10.

An added feature of importance is the fact that the tongue 17a is enclosed within the pocket 15b and even if the clip is violently bent and distorted, this arrangement prevents the outward bending of the movable jaw member 17 which is limited in its motion by the position of the tongue 17a in the pocket aforesaid. The tongue 17a can be bent to adjust or position the amount of the opening between the jaws of the clip thereby insuring that all clips will open a uniform distance, which adjustment is difficult if not impossible to make in other forms of construction.

What is claimed is:

1. A clasp comprising cooperating jaw members, a rectangular spring of arcuate cross section between said members and supported on one of them and having its convex surface in engagement with the other of said members and tend-

ing to urge said members apart, and a locking member engaging said jaw members and in camming relationship therewith and adapted to move said jaw members to closed position and lock same against the tension of said spring.

2. A clasp comprising a stationary jaw member having a flat body portion with upstanding flanges along its sides and ends to form a spring housing, the upper end portion of said member being turned over to engage and hold a movable jaw member in movable operative position, a flat spring lying within said housing and extending into and below said upper end of said member, a movable jaw member having a portion extending under said upper end portion of said stationary jaw member and engaging said spring, and a locking member supported on said stationary jaw member and adapted to press said jaw members onto engagement against the tension of said spring.

3. A clasp comprising a one-piece stationary jaw member having forwardly extending apertured sides forming the side walls of a spring housing and an end portion constituting movable jaw engaging means, a rectangular spring of arcuate cross section in said housing, a movable jaw member engaging said first member and overlying said spring and means for clamping said members together, said means having cam ears extending through said apertured sides of said first member and overlying portions of said second member and adapted to force the latter toward the former against the tension of said spring.

35 4. A clasp comprising a pair of jaw members having interlocking parts with contacting bearing surfaces extending substantially the full width of said members, a spring interposed between said members, and locking means including 40 cam ears overlying one of said jaw members and supported on the other of said members for bringing said members together against the tension of said spring and locking said members in closed position.

45 5. A clasp comprising a one-piece jaw member having a pocket formed therein, a movable member having a tongue projecting into said pocket and adapted to limit the relative movement of said members, gripping surfaces on said members, 50 a rectangular spring of arcuate cross section tending to separate said gripping surfaces while holding said members in operative relationship, and a locking member movably secured to one of said members and having cam ears engaging the 55 other of said members and adapted to lock said members together and in engagement with material gripping therebetween.

60 6. A clasp comprising a stationary jaw member having side walls at its upper end formed with openings, a movable jaw member having an upper end cooperating with the upper end of said first member whereby said movable jaw is limited in its movement in respect to said first jaw, a loop member having side portions extending along the outer faces of said side walls of said first member and end portions engaging into said openings and extending into camming contact with said movable jaw member, and a rectangular spring of arcuate cross section between said members supported on one of them and tending to urge said members apart.
